FIG. 3.

FIG. 4.

Investor Robert Greaves

By his attorney C. J. Davis

UNITED STATES PATENT OFFICE.

ROBERT GREAVES, OF WALLASEY, ENGLAND.

MAGNETIC SEPARATOR.

Application filed March 3, 1923. Serial No. 622,655.

To all whom it may concern:

Be it known that I, ROBERT GREAVES, a subject of the King of Great Britain, and resident of Wallasey, Cheshire, England, have invented certain new and useful Improvements in Magnetic Separators, of which the following is a specification.

The present invention relates to improvements in magnetic separators, more particularly of the type in which the armature of an electromagnet is arranged in the floor of a chute over which material passes, from which material particles of iron are to be separated.

According to the process of the present invention, the material is caused to cascade over a series of magnets arranged in steps, the trailing ends of the armature or pole shoe of the electro-magnets being inwardly bevelled or formed with upstanding shoulders so that particles of iron which would tend to be carried along these surfaces by the flowing stream of material, will on reaching the sharp trailing edges or shoulders of the pole shoes, be caught under or in the angle behind said pole shoes and be brought directly out of the flowing stream of material.

Several types of apparatus for carrying out the invention are illustrated diagrammatically in the accompanying drawings in which Fig. 1 is an elevation and Fig. 2 a plan of a separator the magnetic pole shoes having undercut or bevelled shoulders. Fig. 3 is a fragmentary elevation of a modified form of connecting the series of pole shoes together and Fig. 4 is a fragmentary elevation showing a form of pole shoe with a right-angled shoulder instead of an undercut edge.

In a preferred form of construction, Figs. 1 and 2, a number of magnets 1 are arranged in sequence having their pole shoes 2, the trailing edges 3 of which are bevelled at 4, arranged in sequence and on different levels one above the other so that as the material falls by gravity over the edges 3 of said pole shoes in sequence, the particles of metal passing over the trailing edges will be drawn under the bevelled edges 4, and this effect will be increased by the magnetic attraction of the next pole shoe in sequence.

The pole shoes may be spaced apart from one another by means of non-magnetic pieces. In the arrangement shown in Figs. 1 and 2 the pole shoes forming one surface

are spaced apart by brass or gun metal channel pieces 5 through which are passed pins 6 having tapered ends which enter corresponding holes in the edges of the pole shoes. The 60 pole shoes on one level are connected to those on a lower level by non-magnetic brass or gun metal angle pieces 7, and the magnetic cores 1 are secured to the pole shoes 2 and to a common bridge bar 8 by screws 9 or 65 otherwise. The coils are mounted round the magnetic cores 1 and are energized in any suitable manner.

In the alternative construction shown in Fig. 3 the pole shoes are merely connected together by flat pieces 5^a of some non-magnetic material, the arrangement being otherwise similar to that shown in Fig. 1. In Fig. 4 instead of the shoulders 4^a being undercut they are formed square with the 75 top surface of the pole shoes 2.

With such arrangements, the coils 10, being energized, the lines of force from the pole shoes pass from a higher to a lower level across the undercut edge 4 of the shoulder 4^a developing a strong magnetic field throughout the full width of the chute round the angular cavity *a*. Consequently, as the flowing stream of material cascades over the pole shoes from a higher to a lower level any particles of iron which would otherwise tend to be carried along are drawn into the angular spaces *a* out of the path of the stream of material and are maintained there. In order to remove these separated 80 particles of iron, the current is switched off the electro-magnet coils de-energizing the magnets and permitting the particles of iron to be readily removed.

The action of such an apparatus is very 85 effective in separating particles of iron by reason of the fact that as the lines of force radiate from one shoe at a higher level to another at a lower level and in the same direction as that in which the material is falling over the higher shoe, the particles are under magnetic action for a comparatively long period while passing the cavities *a* and are, therefore, more likely to be trapped therein.

It will be understood that any known 90 means may be used for making the material traverse the apparatus, such as inclining the apparatus, such as shaking means, or shaking means coupled with a suitable inclination of the apparatus.

I claim:

1. A magnetic separator for the extraction of particles of iron or steel from flowing loose material, comprising a series of magnets arranged one behind the other in stepped formation downward from the feeding-in end to the discharge end for the material, said stepped formation providing pockets for the collection and retention of the magnetic particles, at the bottoms of which pockets the upper ends of the pole pieces are located.
2. A magnetic separator for the extraction of particles of iron or steel from flowing loose material comprising a series of magnets arranged one behind the other in stepped formation downward from the feeding-in end to the discharge end for the material, said stepped formation providing pockets for the collection and retention of the magnetic particles, at the bottoms of which pockets the upper ends of the pole

pieces are located, said pole pieces having their tail ends undercut and forming the end walls of the pockets.

3. A magnetic separator for extracting particles of iron or steel from loose material, comprising magnets, arranged in series one behind the other, each successive magnet having its upper pole piece in a lower but parallel plane relative to the pole piece of the preceding magnet to provide a pocket formation stepping downward from the feeding end to the discharge end of the series, over which series the loose material is passed for the extraction of the iron or steel particles into the pockets, at the bottoms of which pockets the upper ends of the pole pieces are located.

In testimony whereof I affix my signature.

ROBERT GREAVES.
